WALFRID LJUNGSTRÖM, OF MATFORS, SWEDEN.

MACHINE FOR PLACING, PRESSING, AND DRYING END CAPS ON PAPER ROLLS.

Application filed November 21, 1925, Serial No. 70,644, and in Sweden October 2, 1924.

In packing the paper rolls obtained in the manufacture of paper, the ends of each roll are covered with caps of millboard or strong paper, jute or the like. The object 5 of these caps is partly to protect the ends of the roll and partly to secure the ends of the paper wrapping that are bent over the edges of the roll. The caps are coated with an adhesive and, up to the present, they have been 10 pressed against the ends of the roll by hand or by two relatively movable press heads. Hand labour, however, is expensive, and in many cases does not turn out very good work while the mechanical means is in many 15 ways objectionable.

The present invention provides a machine for pressing and drying such end caps used in packing paper rolls, by which the work can be done quickly and efficiently. The machine is chiefly characterized by two press heads (heated by steam, electricity or the like) one of which is stationary, whereas the other is arranged in such manner that it can be brought, by means of a screw or other 20 mechanical device, towards the stationary one, for the purpose of pressing caps which have been placed on the ends of a paper roll, said roll being located on a support, so mounted that it is free to move in the same 25 direction as the movable press head to equalize the pressure exerted by the two heads.

In order that the invention may be clearly understood, it will now be described with reference to the accompanying drawings, 30 wherein:

Figures 1 and 1^a together constitute a plan of one form of the machine.

Figures 2 and 2^a together constitute a side elevation of the same, the view being partly 40 in section.

Figure 3 is an end elevation of the same.

Figures 4 and 4^a together constitute a plan of a modification involving an automatically operated machine.

Figures 5 and 5^a together constitute a side elevation of the same.

Figs. 6 and 7 show the starting and stopping mechanism drawn to an enlarged scale, Fig. 6 being a plan view and Fig. 7 a section on line VII—VII in Fig. 6.

Figures 8 and 9 show, partly in section, another construction of the press heads;

Figure 10 shows, in sectional elevation, a third form of the press heads, and Figure 55 11 is an end view of one of said heads;

Figure 12 is an end elevation of one end of a paper roll, with the paper wrapping partly bent over;

Figures 13 and 14 show respectively a sectional elevation and an end view of an auxiliary device to facilitate placing the aforesaid caps on the ends of the paper roll;

Figures 15 and 16 show a fourth form of the press heads; and

Figures 17 and 18 show a fifth form of the press heads.

In the drawings the references 1 and 2 denote the two press heads each of which, in the embodiment illustrated by Figures 1 to 3, is made hollow and provided with a steam inlet 3 and with an outlet 4 for condensed water. The press head 1 is attached to a stationary standard 5, by means of a central ball-joint bracket, to enable the head to adapt itself to the end surface of the roll during the pressing process. The press head 2 is movable and is connected, by means of a ball joint, with a screw 6. This is mounted in a frame 7 supported on wheels 8, 9, so that the whole forms a carriage which can be moved to and fro on rails 10 to facilitate the placing of the press head 2 at a convenient distance from the press head 1 corresponding approximately to the length of the paper roll that is to be packed. In order to fix the carriage in position on the rails when it has been set at the proper distance, it is provided with a brake 11. In addition, screws 12 (Figs. 2 and 2^a), can be caused to engage with the rail so as to lock the carriage in place.

The screw 6 is arranged to be driven by means of an electric motor 13 mounted on the frame 7 and actuating through pinion gearing 14, 15, a reversible double belt drive 16, 17 and pinion gearing 18, 19. The pinion 19 is mounted in two bearing pedestals 20, 21 and the hub of the pinion is provided with, or shaped as, a nut engaged by the screw 6 which is thereby displaced axially 100 in one or the other direction according to the direction of rotation of the pinion, with a consequential displacement of the press head 2. To enable the drive to be reversed without changing the direction of rotation 105 of the driving motor, the belt 16 is uncrossed, whereas the belt 17 is crossed. When the machine is not in operation, the belt 16 runs on an idle pulley 22 while the belt 17 runs on an idle pulley 23 both mounted on the 110

shaft 39 of the pinion 18. They are provided with belt forks 24 and 25 slidable in belt supports 90 and controlled by handles 26 and 27 respectively, by means of which 5 one or other of the belts can be shifted into working position on a pulley 28 fast on the shaft 39. The handles 26, 27 are normally constrained by springs to the inoperative positions shown but when either of them is 10 moved to the operative position it flexes into engagement with a slot 29 in the belt-fork support and is thereby locked.

The construction and operation of the handles 26 and 27 will be more particularly described hereinafter with reference to Figs. 15 6 and 7.

To enable the transmission of power to the screw to be stopped automatically at a predetermined position, a wheel 31, provided 20 with a release cam 30, is arranged opposite the slot 29. This wheel is rotated from the shaft 39 by means of pinion gearing 32, 33 and 34, 35, and a belt 38 running on stepped pulleys 36, 37. At each revolution of the 25 wheel 31 the cam 30 thereon operates a member 40 (Figs. 6 and 7) on the frame 90 thereby forcing the engaged handle out of the slot 29 so that it may spring back into neutral position, the belt 16 or 17, whichever 30 is in action at the time, being thereby moved on to its idle pulley at the same time. Obviously, the timing of the operation of the member 40 can be adjusted by altering the 35 position of the belt 38 on the stepped pulleys.

Between the press heads 1 and 2 is arranged a truck 41, running on rails and intended to support the paper roll in the course of packing. The truck is mounted on 40 wheels 41 so as to be freely movable in the same direction as the movable press head, to equalize the pressure exerted on the roll by the two press heads. For the purpose of lifting the finished roll off the truck 41, the latter is provided with a lever 42.

The machine works in the following manner.

First the carriage supporting the press head 2 is adjusted and clamped on the rails in a position corresponding to the length 50 of the paper roll to be packed, the screw 6 and press head 2 being at this time in position towards the right in Figures 1 and 2. The paper wrapping, which has previously been placed round the paper roll and projects a short distance beyond the edges of same, is turned over at the edges by hand 55 (Figure 12), and the roll is then run on to the truck 41 between the press heads 1 and 2. Paper or millboard end caps, previously 60 coated with a suitable adhesive, are next inserted between the ends of the roll and the press heads 1 and 2, and pressed firmly against the ends of the roll in any suitable manner, as by hand, so as to rest attached 65 to the bent-over edges of the paper wrap-

ping. This having been done, the belt 16 is manually moved into working position on the pulley 28, by means of the handle 26, whereupon the screw 6 travels towards the left (Figure 1) in consequence of the rotation of the pinion 19. In this way the paper roll and the attached end caps are pressed tightly between the heated press heads. As soon as the screw attains the position in which it exerts the pressure required to fix the end caps, the release cam 30 acts on the stop 40, which forces the handle 26 out of the slot 29 and automatically returns the belt 16 on to its idle pulley 22. The movement of the screw 6 is thus stopped, but the paper roll is allowed to remain in this position, gripped between the heated press heads, for about half a minute to complete the packing process. Thereafter the handle 27 is manually moved over to engage in the slot 29, thus moving the crossed belt 17 on to the fixed pulley 28 and causing the pinion 19 to turn in the reverse direction, bringing the screw 6 and press head 2 back into their original positions. Hereupon, the drive is again automatically stopped, the handle 27 being forced out of the slot 29 by the release cam 30 when the wheel 31 has completed a turn in the reverse direction. Finally the packed paper roll is taken off the truck 41 by means of the lever 42, and the machine is ready to deal with another roll.

The press heads 1 and 2 again form the chief parts of the embodiment of the machine shown in Figures 4 and 5. As before, the press head 1 is mounted on the standard 5 by means of a ball-joint bracket while the movable press head 2 is connected, by means of a ball joint, with the screw 6 mounted in the frame 7, this frame being supported on 105 wheels 8, 9, thereby forming a carriage adapted to run on the rails 10. In contrast to the embodiment according to Figures 1 to 3 the carriage is not provided with a braking device, but is free to travel to and fro along the rails 10 during the operation of the machine.

The starting and stopping mechanism which is similar to that described with reference to Figs. 1-3 is clearly shown in Figs. 6 and 7.

Belt forks 24 and 25 mounted on rods 96 and 97 respectively, are provided for shifting the belts, said rods being slidable in the frame 90. The rods are connected by brackets 98 and 99 with handles 26 and 27 respectively, by which one or other of the belts can be shifted into its working position on a pulley 28 fast on the shaft 39. The handles 26 and 27 are fixed at their lower ends and are resilient so that they can be bent or flexed in two directions at right angles to each other. These handles are so fixed that normally they occupy the position shown in full lines in Figs. 6 and 7 (herein- 125 130 135 140 145 150 155 160 165 170 175 180 185 190 195 200 205 210 215 220 225 230 after termed "the inoperative position") but even in this position they tend to flex towards the frame 90 and as shown bear against this frame. In this way when either 5 of the handles is moved longitudinally along the frame, which they can do by flexing, into a position opposite the recess 29 in the frame 90 the handle will flex into the said slot and be retained thereby. This is termed the 10 operative position of the handle because in the movement of the handle into the slot one of the belts is moved on to a fast pulley.

A powerful spring 50 (Figs. 4 and 5) co- 15 axial with the screw 6 is provided, this spring acting between the carriage and a strut 107 which bears against a fixed wall or fixed stand 76, said strut having loose spacing pieces 77 of wood or the like for the purpose of adjusting the machine to deal 20 with paper rolls of different lengths. Moreover this strut is arranged to pass freely into the spring and is provided with an abutment 108 fixed thereon which engages with the end of the spring. On the abutment is 25 mounted a pointer 53 movable over a fixed scale 54 so that the pointer can be set in accordance with the pressure which the press head is to exert upon the paper roll. A lever 51 is provided with a series of holes 52 30 any one of which can receive a pin to pass therethrough and to engage with the abutment 108 so that the position of the lever relatively to the abutment can be adjusted. The lever 51 projects forwardly and is pro- 35 vided near its forward end with a projecting pivot 110 by which it is connected to the cam lever 55 rockably mounted on the stub shaft 111 carried by a bracket 112. The cam lever 55 is so mounted that it is free to move 40 axially on the shaft 111 and on the pivot 110 (Fig. 6) in addition to the rocking move- 45 ment. Moreover the cam lever 55 is also pro- 50 vided with a cam or inclined surface 113 which contacts with a cam or inclined sur- 55 face 114 fixed on the bracket 112. The ar- 60 rangement is such that when the lever 51 is moved the cam lever 55 is rocked and by the action of the cam surfaces 113 and 114 65 is moved towards the lever 26 so as to force it out of the slot 29.

The machine is operated in the same way as the embodiment according to Figures 1 to 3, by means of an electric motor 13 acting through pinion gearing 14, 15 and a re- 55 versible double-belt drive 16, 17. The belt 16 is straight, and the belt 17 crossed. When the machine is put out of operation, the belt 16 runs on the idle pulley 22 and the belt 17 on the idle pulley 23. The belts 16, 17 60 are provided with belt forks 24, 25, respec- 65 tively controlled by handles 26, 27 that are normally constrained to the inoperative po- 70 sition by springs 56 and 57. Power is trans- 75 mitted to the screw 6 by way of the pinion 80 gearing 18, 19. By shifting the belts 16, 17

respectively on to the fast pulley 28, a move- 85 ment in one or other direction is imparted to the screw 6.

The belt forks 24, 25 are controlled in 90 such a way that when the handle 26 is moved into working position in the slot 29, the screw 6 is caused to advance, and pressure is exerted, whereas when the handle 27 is moved into the slot 29, the screw 6 is with- 95 drawn.

The machine according to Figures 1 to 3 100 does not operate automatically, and the han- 105 dles must be manually moved into operative position. This defect is remedied in the embodiment according to Figures 4 and 5, 80 inasmuch as when the screw 6 exerts pres- 85 sure against the end covers of the paper roll, the carriage is forced back and the spring 50 is compressed, thus moving the lever 51 and causing the cam lever 55 to act as hereinbe- 90 fore explained to force the handle out of its original position.

Motion is transmitted from the motor pin- 95 ion 14 to a pinion 58, the shaft of which 100 carries a worm 59. This worm drives a worm wheel 60, the shaft of which carries a small pinion 61 in mesh with a pinion 62 105 provided with an adjustable projection 63 which although adjustable in the slot 66 is 110 normally fixed upon its pinion and is moved round in an arcuate path thereby, and in its movement acts on the belt control handle 27 for the purpose of bringing the same into 115 operative position in the slot 29. Another 120 pinion 64, provided with an adjustable pro- 125 jection 65, meshes with the pinion 61. The projection 65 coacts with the belt control 130 handle 26 to move the same into operative 135 position in the slot 29.

When the motor is started, all the gear 140 mechanism is set in motion and as the pinion 64 rotates, the projection 65 moves the han- 145 dle 26, with its belt fork 24, into operative 150 position in the slot 29, where it remains for 155 the time being. The press screw 6 is set in 160 motion and exerts, through the press head 2, 165 a pressure on the paper roll previously in- 170 serted between the press heads. This causes 175 a gradual rearward movement of the car- 180 rriage and compression of the spring 50. As 185 soon as the required pressure, indicated on 190 the scale 54, is attained, the lever 51 is moved 195 to a position in which it actuates the cam 200 lever 55 to force the spring handle 26 out of 205 the slot 29 which handle then returns to its 210 original position under the influence of the 215 spring 56. This causes the belt 16 to be 220 shifted on to the idle pulley 22, and the 225 movement of the screw 6 ceases. At the 230 same time, however, the projection 63 of the 235 pinion 62 acts on the spring handle 27 and 240 moves it into operative position in the slot 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

screw 6. The peripheral velocity of the pinions 64, 62 and the arrangement of the projections 65, 63 are such that the handles 26, 27 are actuated in a continuous manner at time intervals suitable for the automatic operation of the machine.

Automatic stopping of the reverse movement of the screw 6 is obtained as with the embodiment according to Figures 1 to 3. 10 The wheel 31 (which is provided with a release cam 30 and is actuated from the shaft of the belt pulley 28 through pinion gearing 70, 71 and 72, 73, and belt gearing 74, 75) coacts with the handle 27 in such a way 15 that the cam 30 forces said handle out of the slot 29 when the screw 6 has drawn back far enough to enable a new paper roll to be inserted. This done, the handle 26 is moved back into operative position in the manner 20 already described, and a new pressing operation is performed, the motor 13 running all the time. Hence, the machine can be run by one man, who has merely to insert and remove the paper rolls and keep in readiness the end caps to be applied to the ends 25 of the rolls.

Figures 8 and 9 represent a modified form of the press heads, in which one or more steam coils 43 is or are provided in each 30 head and supported therein by radial webs 91. The movable head 2 is shown but the stationary head 1 is similar. In this embodiment, the heads may be of lighter construction than the heads of the machine illustrated by Figures 1 to 3. Comparatively 35 light press heads can also be used when electric heating resistances are provided therein.

In the embodiment according to Figures 10 and 11, the working faces of the press 40 heads 1 and 2 are each provided with a covering of wire netting 44 or a perforated plate (of sheet copper for example). Said faces may also be perforated or corrugated. The 45 purpose of such arrangement is to prevent the adhesive-coated end caps from being pressed so tightly against the press heads as to become detached from the paper roll under treatment, when the press heads are moved apart again. This may happen in the 50 event of the end caps having, through an oversight, also been coated with adhesive on the side facing the press heads.

One or both of the press heads may be 55 provided with a stamp 45, as shown in Figure 11, so as to impress the end caps in any desired way during the pressing operation. These stamps are interchangeable, so that their lettering, (e. g., the name of the maker, or customer, &c.), may be changed 60 as required.

As shown in Figure 10, the journal 93 carrying the movable press head or the journal 92 carrying the fixed press head or both may be arranged to yield to a certain

extent, being mounted in bushes 46 containing powerful spiral springs 47.

By the aid of two similar auxiliary devices, one of which is illustrated by Figures 13 and 14, the end caps can be placed on the ends of the paper rolls in a convenient 70 manner outside the machine. Each device consists of a springy ring 48 provided with small lugs 49, and is adapted to receive one of the two loose end caps required for each paper roll to be packed. The rings containing the end caps are slipped over the ends of the paper roll 94 (Fig. 12) and grip the same by virtue of their elasticity, whereupon the roll can be easily adjusted in the machine and pressed. In order to hold the end caps in the proper position, each ring may be provided with a metal wire netting 50¹, as shown in Figure 14. Of course, in such case, the wire netting shown in Figure 10, covering the press heads, can be dispensed with.

According to the embodiment shown in Figures 15 and 16, each press head consists of a hollow iron member 78, in which is housed an electric heater 79. A thin plate 80 of steel or other suitable material is provided on the side next the paper roll, and is supported by spring bolts 81, so that it can adapt itself to the raised folds produced by turning over the ends of the wrapping paper, and thus prevent the resulting ridges from being pressed into the roll and damaging the paper.

In the embodiment for the same purpose according to Figures 17 and 18, each press 100 head consists of a hollow member 82 containing a heating device 83. The side next the paper roll consists of radial segments of spring steel 84, which ensure an elastic pressure and adaptability to irregularities 105 on the end surfaces of the paper rolls.

Whilst I have described preferred forms of the machine and parts of the same, it will be understood by those skilled in the art that many modifications may be made, and therefore I intend no limitations upon the invention other than are imposed by the scope of the appended claims.

Having now fully described my invention 115 what I claim and desire to secure by Letters Patent is:—

1. A machine for use in pressing on the end caps of paper rolls enclosed in paper wrapping, comprising a fixed press head, a movable press head, mechanism for moving said movable press head towards said fixed press head for the purpose of pressing the end caps on a paper roll placed between said press heads, and an automatic stop motion for arresting the forward movement of said movable press head.

2. A machine for use in pressing on the end caps of paper rolls enclosed in paper

- wrapping, comprising a fixed press head, a movable press head, and means for automatically reciprocating said movable press head for the purpose of operating automatically on paper rolls placed one after another between said press heads.
3. A machine for use in pressing on the end caps of paper rolls enclosed in paper wrapping, comprising a fixed press head, a carriage, a second press head movably mounted on said carriage, mechanism for moving said movable press head towards said fixed press head for the purpose of pressing the end caps on a paper roll placed between said press heads, and an automatic stop motion for arresting the forward movement of said movable press head.
4. A machine for use in pressing on the end caps of paper rolls enclosed in paper wrapping, comprising a fixed press head a carriage, a second press head movably mounted on said carriage, and means for automatically moving said movable press head towards and away from said fixed press head for the purpose of operating automatically on paper rolls placed one after another between said press heads.
5. A machine for pressing and drying the end caps of paper rolls enclosed in paper wrapping, comprising a fixed press head having provision whereby it may be heated, a movable carriage, a second press head movably mounted on said carriage and also having provision whereby it may be heated, a screw for moving said movable press head for the purpose of pressing and drying a paper roll with its end caps placed between said press heads, and driving means for said screw.
6. A machine for pressing and drying the end caps of paper rolls enclosed in paper wrapping, comprising a fixed press head having provision whereby it may be heated, a movable carriage, a second press head movably mounted on said carriage and also having provision whereby it may be heated, a screw for moving said movable press head for the purpose of pressing and drying a paper roll with its end caps placed between said press heads, driving means for said screw, and mechanism operated by said driving means for automatically stopping the forward motion of said screw when a desired degree of pressure has been attained.
7. A machine for placing, pressing and drying the end caps of paper rolls enclosed in paper wrapping, comprising a fixed press head having provision whereby it may be heated, a movable carriage, a second press head movably mounted on said carriage and also having provision whereby it may be heated, a screw for moving said movable press head for the purpose of pressing and drying a paper roll with its end caps placed

between said press heads, driving means for said screw, and mechanism operated by said driving means for automatically and repeatedly reversing the motion of said screw.

8. A machine for use in pressing on the end caps of paper rolls enclosed in paper wrapping, comprising a fixed press head, a movable press head mechanism for actuating said movable press head for the purpose of pressing the end caps on a paper roll placed between them, a support for the paper roll between said press heads and means for mounting said support so that it is free to move in the same direction as the movable press head, to equalize the pressure exerted on the roll by the two press heads.

9. A machine for use in pressing on the end caps of paper rolls enclosed in paper wrapping, comprising a fixed press head, a movable press head, mechanism for actuating said movable press head for the purpose of pressing the end caps on a paper roll placed between them, an automatic stop motion for arresting the pressing operation, a support for the paper roll between said press heads and means for mounting said support so that it is free to move in the same direction as the movable press head, to equalize the pressure exerted on the roll by the two press heads.

10. A machine for use in pressing on the end caps of paper rolls enclosed in paper wrapping, comprising a fixed press head, a movable press head, means for automatically moving said movable press head towards and away from the fixed press head for the purpose of pressing the end caps on paper rolls placed one after another between said press heads, a support for the paper rolls between said press heads and means for mounting said support so that it is free to move in the same direction as the movable press head, to equalize the pressure exerted on the roll by the two press heads.

11. A machine for use in pressing on the end caps of paper rolls enclosed in paper wrapping, comprising a fixed press head, a movable press head, mechanism for actuating said movable press head for the purpose of pressing the end caps on a paper roll placed between them, a support for the paper roll between said press heads, means for mounting said support so that it is free to move in the same direction as the movable press head, to equalize the pressure exerted on the roll by the two press heads, and means on said carriage to facilitate the removal of the paper roll after the pressing operation.

12. A machine for use in pressing on the end caps of paper rolls enclosed in paper wrapping, comprising two relatively movable press heads, mechanism for actuating said press heads for the purpose of pressing the end caps on a paper roll placed between

them, an automatic stop motion for arresting the pressing operation, a support for the paper roll between said press heads, and means on said support to facilitate the removal of the paper roll after the pressing operation.

13. A machine for use in pressing on the end caps of paper rolls enclosed in paper wrapping, comprising a fixed press head, 10 a movable press head, means for automatically moving said movable press head towards and away from the fixed press head for the purpose of pressing the end caps on paper rolls placed one after another between them, a support for the paper roll between said press heads, means for mounting said support so that it is free to move in the same direction as the movable press head, to equalize the pressure exerted on the roll by the two press heads, and means on said support to facilitate the removal of the paper roll after the pressing operation.

14. A machine for pressing and drying the end caps of paper rolls enclosed in paper wrapping, comprising a fixed head with provision whereby it may be heated, a movable carriage, a second press head movably mounted on said carriage and also having provision whereby it may be heated, a screw 25 for operating said movable press head, and means for driving said screw including a reversible belt drive.

15. A machine for pressing and drying the end caps of paper rolls enclosed in paper wrapping, comprising a fixed head with provision whereby it may be heated, a movable carriage, a second press head movably mounted on said carriage and also having provision whereby it may be heated, a screw 30 for operating said movable press head, means for driving said screw including a reversible belt drive, belt shifting handles, and means for automatically shifting said handles to the inoperative positions to throw said driving means out of operation at the end of each stroke of said movable press head.

16. A machine for pressing and drying the end caps of paper rolls enclosed in paper wrapping, comprising a fixed head with provision whereby it may be heated, a movable carriage, a second press head movably mounted on said carriage and also having provision whereby it may be heated, a screw 45 for operating said movable press head, means for driving said screw including a reversible belt drive, belt shifting handles, means for automatically shifting said handles to inoperative positions to throw said driving means out of operation at the end of each stroke of said movable press head, and means for automatically reversing said belt drive.

17. A machine for pressing and drying the end caps of paper rolls enclosed in paper wrapping, comprising a fixed head with

provision whereby it may be heated, a movable carriage, a second press head movably mounted on said carriage and also having provision whereby it may be heated, spring means in association with said carriage and a fixed abutment, a screw for operating said movable press head relatively to the said carriage, and means for driving said screw including a reversible belt drive and mechanism coacting with said spring means to impart a reciprocating movement to said screw.

18. A machine for use in pressing on the end caps of paper rolls enclosed in paper wrapping, comprising a fixed press head, 50 a movable press head, mechanism for actuating said movable press head for the purpose of pressing the end caps on a paper roll placed between them, a support for the paper roll between said press heads, means for mounting said support so that it is free to move in the same direction as the movable press head, to equalize the pressure exerted on the roll by the two press heads, an automatic stop motion for arresting the pressing operation, and means in association with the working faces of said press heads to prevent the end caps sticking thereto.

19. A machine for use in pressing on the end caps of paper rolls enclosed in paper 55 wrapping, comprising a fixed press head, a movable press head, means for automatically moving said movable press head towards and away from the fixed press head for the purpose of pressing the end caps on paper rolls placed one after another between them, a support for the paper roll between said press heads, means for mounting said support so that it is free to move in the same direction as the movable press head, to equalize the pressure exerted on the roll by the two press heads, and means in association with the working faces of said press heads to prevent the end caps sticking thereto.

20. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head, means for driving said screw including a reversible belt drive, and means in association with the working faces of said press heads to prevent the end caps sticking thereto.

21. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head,

- means in association with said press heads to prevent the end caps sticking thereto, means for driving said screw including a reversible belt drive, belt shifting handles, and means for automatically shifting said handles to the inoperative positions to throw said driving means out of operation at the end of each stroke of said movable press head.
22. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head, means in association with said press heads to prevent the end caps sticking thereto, means for driving said screw including a reversible belt drive, belt shifting handles, means for automatically shifting said handles to inoperative positions to throw said driving means out of operation at the end of each stroke of said movable press head, and means for automatically reversing said belt drive.
23. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head, means for driving said screw including a reversible belt drive, and interchangeable dies for said press heads.
24. A machine for use in pressing on the end caps of paper rolls enclosed in paper wrapping, comprising a fixed press head, a movable press head, mechanism for actuating one of said press heads for the purpose of pressing the end caps on a paper roll placed between them, a support for the paper roll between said press heads, means for mounting said support so that it is free to move in the same direction as the movable press head, to equalize the pressure exerted on the roll by the two press heads and interchangeable dies for said press heads.
25. A machine for use in pressing on the end caps of paper rolls enclosed in paper wrapping, comprising a fixed press head, a movable press head, mechanism for actuating said movable press head for the purpose of pressing the end caps on a paper roll placed between them, a support for the paper roll between said press heads, means for mount-
- ing said support so that it is free to move in the same direction as the movable press head, to equalize the pressure exerted on the roll by the two press heads, an automatic stop motion for arresting the pressing operation, and interchangeable dies for said press heads.
26. A machine for use in pressing on the end caps of paper rolls enclosed in paper wrapping, comprising a fixed press head, a movable press head, a support for the paper roll between said press heads, means for automatically moving said movable press head towards and away from the fixed press head for the purpose of pressing the end caps on paper rolls placed one after another on said support, means for mounting said support so that it is free to move in the same direction as the movable press head, to equalize the pressure exerted on the roll by the two press heads, and interchangeable dies for said press heads.
27. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head, means for driving said screw including a reversible belt drive, and interchangeable dies for said press heads.
28. A paper-roll packing machine comprising a movable and a fixed press head, mechanism for automatically moving said movable press head towards and away from said fixed press head, means in association with said press heads to prevent the material under treatment sticking thereto, interchangeable dies for said press heads, and transportable means for supporting the paper roll during the operation of the machine.
29. A machine for pressing and drying the end caps of paper rolls enclosed in paper wrapping, comprising a fixed press head with provision whereby it may be heated, a movable carriage, a second press head movably mounted on said carriage and also having provision whereby it may be heated, a screw for operating said movable press head relatively to said carriage, means for driving said screw including a reversible belt drive and mechanism co-acting with said spring means to impart a continuous reciprocating movement to said screw, and scale and pointer mechanism in conjunction with said spring means to determine the pressure exerted between said press heads.
30. A machine for use in pressing on the end caps of paper rolls enclosed in paper wrapping, comprising a fixed press head, a

- movable press head resiliently mounted, a support for the paper roll between said press heads, means for automatically moving said movable press head towards and away from the fixed press head for the purpose of pressing the end caps on paper rolls placed one after another on said support and means for mounting said support so that it is free to move in the same direction as the movable press head, to equalize the pressure exerted on the roll by the two press heads.

31. In a paper roll packing machine having two press heads, belt driving mechanisms for operating the heads relative to each other both directly and reversely, handles for controlling the belt driving mechanisms, automatic means for controlling each of the belt driving mechanisms including gearing, and means carried by the gearing to operate the handles in succession. 15

In testimony whereof I affix my signature.

WALFRID LJUNGSTRÖM. 20
